UNITED STATES PATENT OFFICE.

STANLEY F. SWORSKI AND FELIX F. RATAJCZAK, OF MINNEAPOLIS, MINNESOTA.

REPORT FOR GAS-PRODUCING APPARATUS.

1,418,745.

Specification of Letters Patent. Patented June 6, 1922.

Original application filed August 3, 1920, Serial No. 401,020. Divided and this application filed July 18, 1921. Serial No. 485,738.

To all whom it may concern:

Be it known that we, STANLEY F. SWORSKI and FELIX F. RATAJCZAK, citizens of the United States, residing at Minneapolis, in 5 the county of Hennepin and State of Minnesota, have invented certain new and useful Improvements in Retorts for Gas-Producing Apparatus, of which the following is a specification.

10 This invention relates to gas producing apparatus and the main object is to provide an efficient and practical construction of retort or furnace for use in superheating straw or other gas producible materials in such an 15 apparatus. Further objects will be disclosed in the course of the following specification and are illustrated in the accompanying drawings, in which:

Fig. 1 is a side elevation of the furnace, 20 the greater part of the outer shell being broken away for the purpose of illustrating the inner construction.

Fig. 2 is an enlarged section on the line 2-2 in Fig. 1.

25 Fig. 3 is an enlarged section on the line 3-3 in Fig. 1.

This is a divisional application, the same being divided out from the application for patent filed by us for a gas producing apparatus on August 3rd, 1920, Ser. No. 401,020.

Referring to the drawings by reference characters 11 designates a chamber in which the gas is generated and which is suspended in a cylindrical furnace 12, said furnace being provided with a grate 13, fire and ash doors 14 and 15, respectively, and an exhaust stack 16. The furnace is also provided with a guard 17, which supports the grate 13, and two or more oppositely directed horizontal 35 partitions 18, 19 which serve to distribute and more efficiently utilize the heat from the fire on the grate, which heat thus passes around the chamber 11 as shown by the arrows in Figs. 1 and 2. The bottom and 40 lower side portions of the chamber are considerably thicker than its upper part (see Fig. 3) so that it will be more uniformly heated. A snugly fitting bucket 20, having lifting hooks 21, is positioned within the 45 chamber 11.

The chamber 11 is provided at its top with an annular rim 22 which has a bead 23 and a series of spaced perforated ears 24. A cover 25 fits on the rim 22, within the ears 55 24 and has an annular recess adapted to fit over the bead 23. An upwardly extending

bar 26 is fixed in the center of the cover 25 and has threaded to turn thereon a hand wheel member 27. A collar 28 is rotatably held on the member 27 by a plate 29, and is 60 provided with a series of radial extensions 30, to each of which is pivotally mounted one end of a lever 31, the other end of which engages one of the perforated ears 24. Two or three inverted U-bolts 32 engage over the 65 extensions 30 and are bolted to the cover 25, so as to prevent the collar 28 from turning with the handwheel member 27 when the latter is turned. A curved lifting rod 33 is 70 slidably journaled in two brackets 34, and has its upper end pivoted at 35 to the bar 26. The lower end of the rod 33 rests on a cam 36 having a hand lever 37.

Thus when straw or other suitable material has been filled into the chamber 11 the 75 cover 25 can be firmly clamped down in air tight position by means of turning the handwheel 27 which will cause the levers 31 to clamp the cover down and hold it down under very high-pressure. When the contents 80 of the chamber have been exhausted of gas the handwheel 27 is reversed until the levers 31 free themselves from the ears 24. The lever 37 is then pushed down, raising the cover so that it can be swung to either side 85 of the furnace. The bucket 20 is then pulled out and emptied, after which it may again be inserted and the chamber again filled.

As the gas is generated in the retort, as above constructed, it escapes through a pipe 90 38 and into a cooler (not shown) and from there is purified and stored in tanks, as indicated by the application for patent above referred to.

It is understood that various modifications 95 may be made in the design and structure of this retort, provided, however, that such modifications come within the spirit and scope of the appended claims. Having now therefore fully shown and described our invention, what we claim to be new and desire to protect by Letters Patent is:

1. In an apparatus of the class described, a furnace, a gas generating receptacle suspended in the upper part thereof, said receptacle having its bottom and lower wall portion of greater thickness than the upper wall portion, and a bucket adapted to fit snugly in the lower part of said receptacle. 105

2. In an apparatus of the class described, a furnace, a gas generating receptacle suspended in the upper part thereof, said re- 110

ceptacle having its bottom and lower wall portion of greater thickness than the upper wall portion of the receptacle, and a bucket adapted to fit snugly in the lower part of 5 said receptacle, said bucket having an outwardly projecting ledge adapted to rest against the upper part of said lower wall portion of the receptacle.

3. In an apparatus of the class described, 10 a furnace, a gas generating receptacle suspended in the upper part thereof, said receptacle having its bottom and lower wall

portion of greater thickness than the upper wall portion of the receptacle, a bucket adapted to fit snugly in the lower part of 15 said receptacle, and upwardly extending hooked bars secured to said bucket and positioned adjacent the upper part of said receptacle.

In testimony whereof we affix our signatures. 20

STANLEY F. SWORSKI.
FELIX F. RATAJCZAK.
